DESIGN FOR A DISPLAY STAND FOR GREET-
ING CARDS OR THE LIKE

Louis Katz, New York, N. Y.

Application July 27, 1946, Serial No. 132,034

Term of patent 14 years

(Cl. D80—9)

To all whom it may concern:

Be it known that I, Louis Katz, a citizen of the United States of America, residing in the Borough of Manhattan, city, county, and State of New York, have invented a new, original, and ornamental Design for a Display Stand for Greeting Cards or the like, of which the following is a specification, reference being had to the accompanying drawings, forming part thereof, wherein:

Figure 1 is a front elevation of the display stand embodying my new design.

Fig. 2 is a top plan of the display stand shown in Fig. 1.

Fig. 3 is a section taken along the plane of the line 3—3 of Fig. 1.

I claim:

The ornamental design for a display stand for greeting cards or the like, as shown.

LOUIS KATZ.
